WALTER L. C. NILES, OF SAUGUS, MASSACHUSETTS, ASSIGNOR TO EXCEL SHOE FORM COMPANY, OF LYNN, MASSACHUSETTS, A CORPORATION OF MASSACHUSETTS.

PROCESS OF MAKING SHOE-FORMS.

1,127,080.

Specification of Letters Patent. Patented Feb. 2, 1915.

Application filed September 22, 1914. Serial No. 862,016.

To all whom it may concern:

Be it known that I, WALTER L. C. NILES, citizen of the United States, residing at Saugus, county of Essex, State of Massachusetts, have invented a certain new and useful Improvement in Processes of Making Shoe-Forms, of which the following is a specification, reference being had therein to the accompanying drawings.

10 My invention relates to a new and improved process of producing hollow display forms for boots and shoes, and relates especially to that class of such forms which are covered in at the angle opening. I am 15 aware that heretofore so-called covered in forms have been produced in various ways but, so far as known to me, the methods of producing them have been unduly expensive and furthermore the forms themselves have 20 not been perfectly shaped about the ankle portion.

The object of my invention is to produce a covered in form out of a single sheet of material by a simple and inexpensive process, so that the form will be accurately 25 shaped to the configuration of the last.

My invention will be fully understood from the following description, when taken in connection with the accompanying drawings and the novel features thereof will be clearly pointed out and defined in the claims at the close of the specification.

In the drawings.—Figure 1 is a plan view of a blank from which the form is produced. 35 Fig. 2 is a view of the blank shown in Fig. 1 which has been folded over and submitted to a crimping operation. Fig. 3 shows the crimped blank died out to the pattern desired, the meeting edges of the heel portion 40 being secured together by stitches. Fig. 4 is a side elevation of the blank shaped over a mold or last and having curved side plates which cause the blank to conform to the in-curved sides of the mold, that portion of 45 the blank at the ankle extending above the mold. Fig. 5 is a section on line 5—5 of Fig. 4. Fig. 6 is a view similar to Fig. 5 showing the projecting edges above the ankle drawn tightly together over the mold. Fig.

7 is a side elevation of the form after the 50 side plates, clamps and mold shown in Fig. 6 have been removed. Fig. 8 is an elevation of the finished form, the mold and the contiguous upwardly extending edges having been removed. Fig. 9 is a section on line 55 9—9 of Fig. 8. Fig. 10 is a plan view of the finished form shown in Figs. 8 and 9.

Having reference to the drawings, there is shown in Fig. 1 a blank A which consists of leather board or other like sheet material 60 such as is adaptable for use in the manufacture of hollow shoe forms. The blank is blocked out in the shape shown, having a toe portion B, a heel portion C and an ankle opening D.

The blank is subjected to a crimping operation which is customarily employed to form the instep E of the form as shown in Fig. 2. In order to accomplish this it must be first properly tempered as is well known to 65 those skilled in the art so that it is pliable and readily adapted to be shaped in the crimping machine. After it is crimped the edges are cut to the pattern desired by a die which roughly conforms the blanks to the 70 required size. Then the rear edges of the blank are stitched together as shown at F in Fig. 3. The properly tempered blank is then placed over a mold G and secured thereto in the ordinary manner as by tacks 75 or the like. The blank is so shaped that after it has been properly secured to the mold G the edges H at the ankle opening D extend well above the top of the mold, as shown in Figs. 4 and 5. At the sides of 80 the mold the blank is secured by curved side plates I. These operate to hold the material in close conformity to the in curves of the mold. While the blank is still in the proper temper the upwardly projecting portions 85 thereof are bent over the top of the ankle portion of the mold to form horizontal top covering portions M and contiguous up-turned portions, the turned-up portion being drawn tightly together by means of any suitable clamping device as for instance by clamps P so that the turned edges H come together along the median line of the ankle 90 95

top, as is clearly shown in Figs. 6 and 7, and the blank is drawn closely up around the mold. These clamps may be used for performing the bending as well as the drawing up. This drawing up action by the clamps P will pull the blank in a flat plane across the incurved side of the mold unless some means are provided to cause the blank to follow the curve. For this reason the side plates I are employed which cause the blank to conform to the curve and retain it in that form while it is being drawn up by the clamps. By this process the sides K of the blank which are held in conformity to the shape of the last by the side plates I are stretched upwardly about the last, and at the same time the ankle covering is formed by the portions M. Thus the whole blank including the ankle covering is all molded to the required shape. The clamps and side plates should be allowed to remain until the material has been completely dried out and set, and then the clamps, side plates and mold are removed. After the blank thus shaped has become dried the upwardly projecting contiguous portions of the edges H may be removed by a suitable knife, being severed flush with the upper surface of the form thus giving it the finished appearance shown in Figs. 8, 9 and 10. The edges of the flat, horizontal top portions M come together at L along the median line of the ankle opening and are held firmly together by the sewing F along the heel portion. It will thus be seen that it is not essential to secure the covering members together in any way along the meeting edges.

If it is desired, the portions M may be covered by a thin piece of sheet material. This may be cemented on and trimmed off at the edges by a suitable knife. Sheet material used for this purpose may of course be very thin and, therefore, easily cut, and it operates as a covering or finish.

By the process above described the form is made to conform more accurately to the shape of the mold than by any method heretofore employed so far as I am aware, and it is more economical of production.

What I claim is:

1. The process of producing a covered-in hollow shoe form out of a single blank of properly shaped and tempered sheet material, said process consisting of molding and clamping the tempered blank to a mold, in such manner that the top edges of the blank are bent in toward each other over the top of the ankle portion of the mold until they meet together on the top of the ankle portion of the mold, then allowing the blank to dry while thus shaped and clamped to the mold, and then removing the mold from the form.

2. The process of producing a covered-in

hollow shoe form out of a single blank of 65 properly shaped and tempered sheet material, said process consisting of shaping and clamping the tempered blank to a mold, in such manner that the top edges of the blank are bent in toward each other over the top 70 of the ankle portion of the mold until they meet together on the top of the ankle portion of the mold and terminate in upwardly extending contiguous portions forming a fin, then allowing the blank to dry while 75 thus shaped and clamped to the mold, and then removing the mold from the form and trimming off the said fin.

3. The process of producing a covered-in hollow shoe form out of a single blank of 80 properly tempered sheet material having a portion which is to form the covered-in top ankle portion, said process consisting of crimping the blank, placing the crimped blank onto a mold, said covering in portion 85 being so formed that when the crimped blank is placed on the mold the edges of the blank extend above the top of the ankle portion of the mold, then drawing up the blank to fit the mold and bending the said upwardly extending portions of the blank over the top of the ankle portion of the mold until they meet together and terminate in upwardly extending contiguous portions 90 forming a fin, then allowing the blank 95 to dry while shaped and clamped to the mold, and then removing the mold from the form and trimming off the said fin.

4. The process of producing a covered-in hollow shoe form out of a single blank of 100 properly tempered sheet material consisting of crimping the blank to form the instep portion, then placing the crimped and tempered blank on a mold and bending the top edges of the blank over the top of the ankle portion of the mold, and clamping the form to the mold and allowing it to dry while 105 clamped to the mold.

5. The process of producing a covered-in hollow shoe form out of a single blank of 110 properly tempered and crimped sheet material, consisting of inserting a mold into the crimped blank, fastening the blank to the mold by side clamps which conform to the incurved sides of the mold, then drawing up 115 the upper portions of the blank and bending them over the top of the ankle portion of the mold until the two opposite upwardly extending portions of the blank meet together on the top of the ankle portion of 120 the mold, and allowing the blank thus shaped to dry while clamped to the mold.

6. In the process of making hollow shoe forms out of a blank of properly tempered sheet material, fitting the blank over a mold, 125 applying to the sides of the blank incurved retaining plates which conform to the incurved sides of the mold and securing said

plates and blank to the mold, then bending the upwardly extending opposite side portions of the blank and clamping them over the top of the ankle portion of the mold 5 and allowing the blank to dry while thus mounted on the mold.

In testimony whereof I affix my signature, in presence of two witnesses.
